UNITED STATES PATENT OFFICE.

ALFRED MARX, OF PARIS, FRANCE.

ELECTROCENTRIFUGAL SEPARATOR.

Application filed July 13, 1923. Serial No. 651,376.

To all whom it may concern:

Be it known that I, ALFRED MARX, of 162 Boulevard Voltaire, Paris, France, engineer, have invented Electrocentrifugal Separators, of which the following is a full, clear, and exact description.

It is known that if an electric field is caused to pass in a liquid or gaseous fluid containing liquid or solid particles in fine suspension or in a colloidal condition, these particles tend to move in a determined direction.

This phenomenon is generally called cataphoresis and the known apparatuses based on this phenomenon usually comprise two metallic cylinders concentrically arranged within each other so as to form an annular conduit through which circulates the fluid to be treated.

20 The two cylinders, electrically insulated from each other, are respectively connected to the two poles of a suitable source of electricity, so that between these two electrodes an electric field is produced and that the 25 particles in suspension in the fluid are electrified and projected on the inner surface of the outer cylinder.

In these apparatuses, the whole of the 30 two cylinders is fixed so that, when the stream of fluid passes through the apparatus, it often draws with it a certain quantity of the particles projected on the inner wall of the outer cylinder and, usually, this fluid comes out of the apparatus only incompletely freed from the particles which were in 35 suspension therein.

This invention is adapted to remedy this inconvenience and consists, substantially in 40 imparting to the apparatus a rotary movement, so that the particles, projected by the electric action, are also projected by the action of the centrifugal force and that they thus firmly adhere to the wall on which they are projected; the particles will be caught 45 on the inner face of the outer electrode if their density is greater than the fluid to be treated and on the outer face of the inner electrode if their density is lower than that of the said fluid.

50 The present invention has therefore for its object a process for the electrocentrifugal separation characterized by the fact that the action of an electric field, and of centrifugal force are utilized simultaneously 55 for the purpose of obtaining a complete and accelerated separation of the liquid or solid

particles contained in suspension in any liquid or gaseous fluid.

In order that the invention may be clearly understood, various forms of construction 60 of the apparatus forming the subject-matter of this invention will be described hereafter, by way of example only, with reference to the accompanying drawing, in 65 which:

Fig. 1 is a longitudinal vertical section of a one form of construction of electrocentrifugal separator.

Fig. 2 is a horizontal section taken on line A—A of Fig. 1.

Fig. 3 is a partial diagrammatic vertical longitudinal section of an electro-centrifugal separator having a capillary action.

Fig. 4 is a similar view showing an electro-centrifugal separator provided with a 75 rotary bowl of small diameter.

Fig. 5 is a section of an electro-centrifugal separator provided with a centripetal filtrating device.

In the form of construction illustrated in 80 Figs. 1 and 2 of the accompanying drawing, the apparatus comprises a bowl 1 having solid walls, internally provided with radial blades or vanes 2 and rigidly mounted on a vertical shaft 3 which can receive a rotary 85 movement in a frame 4 of suitable shape.

On the upper end of the shaft 3 is pressed any contact member 5, brush or the like, connected to an electric source, in such a manner that the cylindrical wall of the bowl 90 1 is in communication with one of the poles of the said source.

Within this bowl is concentrically arranged a cylindrical metallic ring 6 against which is also pressed a brush 7 putting in 95 communication the second pole of the electric source with the said ring 6 which, suitably centered between the blades or vanes 2 of the bowl, is electrically insulated from the latter by insulating packings 8 secured 100 on the edge of the said vanes and by covering members 9 and 10 of insulating material respectively pressed on the bottom and the central portion as well as on the inner face of the upper ledge of the bowl, as clearly 105 shown at 10 in Fig. 1.

The apparatus described above is fed with the fluid to be treated which, contained in the reservoir 11, flows in a continuous manner through the conduit pipe 12 on the bottom of the bowl 1 which it fills annularly, under the action of centrifugal force, be-

2
tween the inner face of the bowl 1 and the outer face of the cylindrical sleeve 6 arranged in the latter.

This sleeve 6 forming the central electrode 5 might of course rotate with the bowl 1 or it might be fixed and suspended in the latter by any suitable means.

If the fluid to be treated is a liquid containing a fine or colloidal suspension (water 10 and sulphur) for instance, the solid particles, under the combined actions of centrifugal force and of the difference of potential produced by the electric action in the centrifugated liquid, settle on the wall of the 15 bowl 1, if their density is greater than that of the liquid treated or on the wall of the sleeve 6, if their density is lower than that of the said liquid.

This sediment is obtained much more rapidly 20 than under the action of centrifugal force alone or than under the electric action alone of the apparatus, devised in accordance with the invention, has the important advantage of ensuring not only the complete and rapid 25 separation of the particles in suspension in a fluid, but also the fixing of these latter on the walls of the apparatus, so that the said fluid which, in the form of construction illustrated, is collected at the upper part of 30 the apparatus by the discharged conduit pipe 13 is completely freed from the said particles, whether the latter are solid, as in the above mentioned example, or liquid, as in the case the product to be treated is oil, 35 for example.

In the form of construction illustrated in Fig. 3 of the accompanying drawing, the electro-centrifugal separator is composed of a bowl 1 rigidly secured on a vertical shaft 3 40 receiving in a frame of suitable shape, a rotary movement of high speed.

On a suitable point of this shaft is held any contact member 5, brush or the like, connected to a source of electricity 14, so that 45 the said shaft, as well as the socket 15, integral with the bowl 1 and feeding in the latter the liquid to be treated, are in constant communication with one of the poles of the said source.

50 The cylindrical wall of the bowl 1 is, on the other hand, electrically connected to the other pole of the same source by a suitable contact member 16, brush or the like, and is insulated from the inlet socket 15 for the 55 fluid by a packing 17, made of suitable insulating material.

Within this bowl is arranged a series of plates in close proximity to each other between which the fluid treated, fed into the 60 bowl in the known manner through the socket 15, is divided in capillary sheets.

These superposed plates are each constituted by two metallic surfaces which, in the example shown, have the shape of frusta 18 65 and 19 fitting in each other and electrically

insulated from each other by a packing 20 made of any insulating material.

The various conical elements 18 are connected together as, for instance, in the form of construction illustrated, by metal rods 21 70 which are secured at their upper end by a circular ledge of the upper plate 22.

The plates 18, 19, which are perforated at 18^a, 19^a and in close proximity to each other in the usual manner, are held at the desired 75 distance apart for dividing the fluid to be treated in capillary sheets, by small discs which may be of any suitable arrangement and, in the example described, are constituted by members of insulating material 23. 80

The upper plate 22 is extended above the set of plates in the shape of a cylindrical sleeve 24 fitting in the upper cylindrical portion of the bowl 1; this upper plate is in direct contact with the bowl 1, so that the elements 18 secured by the rods 21 to the said plate 22, are electrically connected to the same pole as the outer portion of the bowl. 85

The upper part of the bowl 1 is, on the other hand, insulated by a packing of insulating material 27 from the central socket 15, which is electrically connected, on the one hand, to the elements 19 of the plates and, on the other hand, through the shaft 3, to the 90 other pole of the source of electricity. 95

In the apparatus described above, the fluid to be treated, introduced in a continuous manner in the vessel 29, passes down through the socket 15, enters through the conduit pipes 30 presented by the latter into the bowl 1 and passes through the holes 18^a, 19^a of the plates 18, 19 in the capillary interval between these latter. 100

Under the combined actions of centrifugal force and of the difference of potential produced by the electric action in the centrifugated fluid, the latter which may, for instance, be a mixture of liquids of different densities, separates into its constituent elements, the heavy liquid moves towards the cylindrical wall of the bowl 1, ascends above the nonperforated upper plate 22 and is exhausted through the orifices 31. The light liquid moves towards the axis of the apparatus by ascending in the capillary intervals separating the plates and is exhausted through the orifices 32 of the upper plate 115 and of the bowl 1.

In the form of construction shown in Fig. 4, the bowl is in the shape of a tube 1 of circular cross section, rigidly secured on a vertical shaft receiving in the known manner, a rotary movement of very high speed. 120

This tubular bowl 1 is electrically connected, as explained above, to one of the poles of a source of electricity by a suitable contact member 5 and encloses a second metallic tube 6 of circular cross section which, concentrically arranged within the said bowl and centered between the vanes 2 is 125

- electrically insulated from the latter by insulating packings 9 and is connected by a suitable conductor to the second pole of the source of electricity.
- 5 The fluid to be treated, admitted in a continuous manner in the bowl 1 through the orifices 12 fills, during the operation of centrifugation, the annular interval comprised between the bowl 1 and the inner tube 6 and 10 separates into its constituent elements; the heavy liquid moves towards the wall of the bowl 1 and is exhausted through the orifice 31, whilst the light liquid moves towards the axis of the apparatus and is exhausted 15 through the orifice 32, as explained above.
- In the form of construction shown in Fig. 5, the bowl 1 is in the shape of a cylinder which receives, on the vertical shaft which carries it, a rotary movement of high speed.
- 20 This cylindrical bowl, electrically connected to one of the poles of a source of electricity as previously explained encloses, at its lower part, a perforated cylindrical or conical sleeve 6^a on the outer surface of 25 which is fitted a suitable filtering element (paper, fabric, etc.).
- This sleeve 6^a is electrically insulated from the bowl 1 by means of insulating packings 9 suitably arranged and is connected to the 30 second pole of the source of electricity to which is connected the bowl 1.
- The fluid to be treated, fed in a continuous manner by the conduit pipe 12 takes in the bowl 1 the shape of an annular crown flooding, at its lower part, the sleeve 6^a. This 35 fluid separates into its constituent elements: the heavy product settles on the wall of the bowl 1 and the lighter liquid passes through
- the filtering element and flows away through the orifice 32.
- The constructional arrangements described above are, of course, given by way of example only, the forms, materials and dimensions of the various constituent parts as well as the details of construction may be varied 40 without departing thereby from the principle of the invention.
- Claims:
1. A process for the separation of suspensions or emulsions, characterized essentially by the fact that the product to be treated is subjected simultaneously to the action of an electric field and of centrifugal force, whereby to obtain rapid and complete separation of the particles which are in suspension in the fluid to be treated.
- 50 2. An electro-centrifugal separator essentially constituted by two metallic cylindrical surfaces concentrically mounted the one in the other, so as to provide between them an annular space in which circulates the product to be treated, these surfaces, electrically insulated from each other, being respectively, connected to the two poles of a source of electricity, and receiving a movement of rotation about their common axis, for the purpose of producing, in the product treated, a difference of potential suitably established at the same time as the centrifugation of the said product and of thus accelerating the separation of the particles in suspension in the latter.
- 60 65 70 The foregoing specification of my "Electro-centrifugal separator", signed by me this 29th day of June 1923.

ALFRED MARX.
